Primary Examiner — Brett Miller(74) *Attorney, Agent, or Firm* — Donald J. Ersler(57) **CLAIM**

The ornamental design for a corrosion control facility, as shown and described.

DESCRIPTION

FIG. 1 is a top perspective view of a corrosion control facility incorporating our new design;
FIG. 2 is a rear perspective view thereof;
FIG. 3 is a bottom perspective view thereof;
FIG. 4 is a top plan view thereof;
FIG. 5 is a bottom plan view thereof;
FIG. 6 is a left side view thereof;
FIG. 7 is a right side view thereof;
FIG. 8 is a front view thereof; and,
FIG. 9 is a rear view thereof.

Any surface with an inner broken line perimeter inside an outer solid line perimeter are part of the claimed invention. The broken lines shown in the drawings illustrate portions of the corrosion control facility that form no part of the claimed invention.
